UNITED STATES PATENT OFFICE.

ANDREW R. BLACKSTONE, OF SAN DIEGO, CALIFORNIA, ASSIGNOR OF ONE-FOURTH
TO WILLIAM D. CHAMBERLAIN, OF SAN DIEGO, CALIFORNIA.

BOILER.

Application filed July 20, 1922. Serial No. 576,229.

To all whom it may concern:

Be it known that I, ANDREW R. BLACKSTONE, a citizen of the United States, residing at San Diego, in the county of San 5 Diego and State of California, have invented a certain new and useful Boiler, of which the following is a specification.

My invention relates to boilers more particularly to high pressure transportable 10 boilers for producing the steam for self propelled vehicle engines and the objects of my invention are: First, to provide a boiler of this class in which the crown sheet or portions of the boiler subjected to the frame 15 of the burner are covered by the liquid within the boiler at all times irrespective of a substantial angular tilting of the boiler; second, to provide a boiler of this class in which the usual trouble of blowing out tubes 20 in the conventional boiler will be eliminated; third, to provide a boiler of this class with novel heat conducting and distributing units; fourth, to provide a boiler of this class in which the heat conducting and distributing units are not exposed to the direct 25 fire; fifth, to provide a boiler of this class with novel heat retaining and distributing means; sixth, to provide a boiler of this class with substantially instantaneous steam 30 generating and superheating means; seventh, to provide a superheater in connection with the boiler which will be filled with steam almost immediately after starting the main burners of the cold boiler, thus preventing 35 injury by heat to the superheater as is usual with the superheater of the conventional boiler of the transportable type; eighth, to provide a novel fuel gasifying means; ninth, to provide a novelly constructed 40 boiler of this class; tenth, to provide a boiler of this class in which the scale accumulation is reduced to a minimum and eleventh, to provide a boiler of this class which is very simple and economical 45 of construction, durable, compact, efficient, easy to operate and which will not readily deteriorate or get out of order.

With these and other objects in view as will appear hereinafter my invention consists of certain novel features of construction, combination and arrangement of parts and portions as will be hereinafter described in detail and particularly set forth in the appended claims, reference being had to the 55 accompanying drawings and to the charac-

ters of reference thereon which form a part of this application in which:

Figure 1 is a plan view of my boiler with portions broken away and in section to facilitate the illustration; Fig. 2 is a partial elevational and partial sectional view thereof taken at 2-2 of Fig. 1; Fig. 3 is a sectional view thereof taken at 3-3 of Fig. 1 showing certain parts and portions in elevation to facilitate the illustration; Fig. 4 is a horizontal sectional view of a portion of my boiler taken at 4-4 of Fig. 3 showing the arrangement of the burners, superheater, gasifier and the like; Fig. 5 is a sectional view taken through 5-5 of Fig. 4 with certain portions shown in elevation to facilitate the illustration and Fig. 6 is a fragmentary elevational view taken at 6-6 of Fig. 5 showing the gasifier and pilot burner.

Like characters of reference refer to similar parts and portions throughout the several views of the drawings.

The steam and water receptacle members 1 and 2, bolts 3, nut 4, steam generating coil 5, superheating coil 6, plug 7, burner members 8 and 9, brackets 10, gas tube 11, gasifying member 12, gasifying burner 13, pilot tubes 14, pilot tubes 15 and the heat retaining member 16 constitute the principal parts and portions of my boiler structure.

The boiler proper consists of a lower steam and water receptacle member 1, and an upper steam and water receptacle member 2, both preferably made of Lyonite or other metal having great strength and a high factor of heat conductivity. The lower receptacle member 1 is made frusto-conical in shape at its central portion 1^a with another larger inverted frusto-conical portion 1^b secured over and to the portion 1^a at 95 its lower end. The portion 1^a is provided at its upper end with an upwardly extending slightly tapered tube portion 1^c. Said frusto-conical portion 1^a is also provided with a plurality of thin fins 1^d and 1^e extending from near the lower end thereof in gradually widening bands to and over the top thereof, the fins 1^d terminating in the upwardly extending tube portion 1^c, the others 1^e being slightly spaced therefrom. Said lower receptacle member 1 is provided at the upper end of the larger frusto-conical portion 1^b with a flange 1^f and an upwardly tapering annular flange 1^g adapted to engage a similar flange 2^a and recess 2^b respectively.

in the upper receptacle member 2. Said member 2 is also frusto-conically shaped, closed at its upper end and provided with a tapered hole 2^c to receive the tapered tube 5 portion 1^c of the member 1. Said receptacle members are secured together at their flanges 1^f and 2^a with bolts 3, and by a locknut 4 engaging the upper end of the tube portion 1^c of the member 1 extending 10 through and above the tube 2^c in the member 2. A steam generating coil 5 is provided in the recess formed by the frusto-conical portion 1^a of the member 1 and is connected at its lower end to the lower portion of the receptacle member 1 by conductor 5^a and is 15 connected at its upper end to the top of the receptacle member 2 above the water level by the conductor 5^b extending through the tubular portion of the receptacle member 1. 20 A superheater or superheating coil 6 is also provided in said recess and the various coil portions of said coil are positioned between the various coil portions of the steam generating coil 5 forming a substantially continuous cylindrical vertical wall. Said coil 6 is similarly connected at its upper end to the top of the receptacle member 2 by a conductor 6^a similarly extending through the tubular portion of the receptacle member 1. 25 Said superheating coil 6 is also provided with a conductor 6^b at its lower end to connect the boiler with an engine not shown in the drawings. A plug 7 is provided at the lower end of the tapered tubular portion 1^c 30 of the receptacle member 1 to retain the heat in the recess occupied by said coils. The burners supplying the heat for the boiler are preferably made in two sections 8 and 9. The inner burner member 8 is 35 slightly larger at its inside diameter than the outside diameter of the coil and is provided on one side with an opening 8^a to facilitate the removal of the same without removing said coils or disconnecting the 40 same. The burner member 9 is similarly constructed and extends around the burner member 8. Said burners are supported on and spaced by the brackets 10 which are secured to the wall of the receptacle member 1. 45 The burner members 8 and 9 are each provided with downwardly extending tubular portions 8^b and 9^a respectively and are connected at their lower ends to the conductors 11^a of the gas tube 11, which conductors extend upwardly some distance into the tubular portions of the burners and spaced from the wall thereof to also admit air to the burner. The gasifying burner 13 is positioned within and at the lower end of the 50 coils 5 and 6 and is supported on the members 13^a secured to the receptacle member 1. Said burner receives its fuel supply by the conductor 13^b connected to an acetylene generator not shown in the drawings. The gas tube 11 extends upwardly through said 55 burner 13 and is provided at its upper end with a gasifying member 12, which is spherical, said tube extending near the top thereof. Said member 12 is also provided with a fuel conductor 14 which is adapted to 70 conduct fuel oil to the gasifying member 12 for the burner members 8 and 9. A valve 14^a is provided in the fuel conductor 14 to regulate the fuel feed and therefore the steam generated. The gasifying burner 13 75 is provided with outwardly extending and upwardly directed pilot tubes 15, the ends of which are positioned adjacent the downwardly extending tubular portions of the burner members which are provided with 80 orifices or slots in close proximity to each other and are adapted to direct a flame alongside said tubular portions of said burner members to ignite the gases escaping from the orifices therein. The heat retaining member 16 consists of helically drawn discs or sectors secured together and spaced from each other preferably as shown in the drawings. Said member 16 is preferably supported by clips 16^a secured to the 85 receptacle member 1. The boiler receives its supply of fresh water through the conductor 17, provided at the upper portion of the receptacle member 2, in the conventional manner. 90

Fuel oil is admitted in regulated quantities, by means of the valve 14^a, into the spherical gasifying member 12 in which said fuel oil is gasified in regulated quantities depending upon the amount of steam required to be generated. This gasified fuel is discharged through the gas tube 11 into the conductors 11^a and thence into the tubes 8^b and 9^a of the burner members 8 and 9, 100 respectively. This gasified fuel is mixed with air which is admitted to the tubes 8^b and 9^a between the same and the conductors 11^a, the mixed fuel and air passing through the tubular portions of the burner members and out of the orifices or slits provided 105 therein where the mixture is ignited. The resulting burnt gases of combustion are by necessity forced downwardly by reason of the upper end of the recess of the receptacle member 1 being closed. Said gases of combustion are forced to take a helical downward path through the passage provided by the helically drawn discs of the heat retaining member 16. The heated gases of combustion, when being forced downwardly, 110 heat the inner walls of the member 1 and therefore spend most of their energy in heating the water of the boiler before being exhausted at the lower end of the boiler. 115

Though I have shown and described a particular construction, combination and arrangement of parts and portions I do not wish to be limited to this particular construction, combination or arrangement but desire to include in the purview of my in- 120 125 130

vention the construction, combination and arrangement substantially as set forth in the appended claims.

Having thus described my invention what 5 I claim as new and desire to secure by Letters Patent is:

1. A boiler of the class described, including a steam and water receptacle provided with a recess extending inwardly from the 10 bottom thereof, a burner positioned in the recess of said receptacle near the upper end thereof, a superheating coil positioned in said recess contiguous to said burner and connected to the receptacle above the normal 15 water level therein and downwardly inclined heat distributing plates mounted in said recess below said burner.

2. A boiler of the class described, including a steam and water receptacle provided 20 with a recess extending inwardly from the bottom thereof and provided with a plurality of thin substantially vertical heat conducting fins within said receptacle and on the wall thereof forming said recess, a 25 burner positioned in the recess of said receptacle near the upper end thereof, a superheating coil positioned in said recess contiguous to said burner and connected to the receptacle above the normal water level 30 therein and downwardly inclined heat distributing plates mounted in said recess.

3. A boiler of the class described, including a steam and water receptacle provided with a recess extending inwardly from the 35 bottom thereof, a burner positioned in the recess of said receptacle near the upper end thereof, a steam generating coil positioned in said recess contiguous to said burner and connected with the inside of said receptacle at the upper and lower portions thereof, a superheater also positioned in said recess 40 contiguous to said steam generating coil and connected to said receptacle above the normal water level therein, substantially helically shaped heat distributing members positioned in said recess contiguous to said steam generating coil and superheater and the wall forming the recess within said receptacle.

4. A boiler of the class described including a steam and water receptacle provided with a recess extending into said receptacle, 50 a burner positioned in the recess of said receptacle, a superheating coil positioned in said recess contiguous to said burner and connected to the receptacle above the normal water level therein and substantially 55 helically shaped heat distributing members positioned in said recess between said superheating coil and the wall forming said recess.

5. A boiler of the class described, including a steam and water receptacle provided 60 with a recess extending into said receptacle, and provided with a plurality of thin substantially vertical heat conducting fins within said receptacle and on the wall thereof forming said recess, a burner positioned in

the recess of said receptacle, a superheating coil positioned in said recess contiguous to said burner and connected to the receptacle above the normal water level therein and substantially helically shaped heat distributing members positioned in said recess 70 between said superheating coil and the wall forming said recess.

6. A boiler of the class described, including a steam and water receptacle provided 75 with a recess extending into said receptacle, a burner positioned in the recess of said receptacle, a steam generating coil positioned in said recess contiguous to said burner and connected with the inside of said receptacle at the upper and lower portions thereof, a superheater positioned in said recess contiguous to said steam generating coil and connected to said receptacle above the normal water level therein and substantially 80 helically shaped heat distributing members positioned in said recess contiguous to said steam generating coil and superheater and the wall forming the recess within said receptacle.

7. A boiler of the class described, including a steam and water receptacle provided with a recess extending into said receptacle, a burner positioned in the recess of said receptacle, a steam generating coil positioned in said recess contiguous to said burner and connected with the inside of said receptacle at the upper and lower portion thereof, a superheater also positioned in said recess 95 contiguous to said steam generating coil and connected to said receptacle above the normal water level therein, substantially helically shaped heat distributing members positioned in said recess contiguous to said steam generating coil and superheater and the wall forming the recess within said receptacle, another burner positioned contiguous to said steam generator coil and said superheater, a fuel gasifying means positioned above said latter burner, conductors connecting said gasifying means with said first mentioned burner and a fuel supply tank.

8. A boiler of the class described, including a lower steam and water receptacle member provided with an upwardly extending recess and a plurality of substantially vertical heat conducting fins extending outwardly from the wall forming said recess and provided with an upwardly extending tubular portion connecting with said recess, an upper receptacle member secured to said lower receptacle member provided with an opening in the upper portion thereof to receive the upwardly extending tubular portion of said lower receptacle member forming a water tight compartment between the walls of said receptacle members, circular burner members positioned in the recess of said lower receptacle member near the top 115 120 125 130

thereof, a superheating coil positioned centrally in said recess below said burner and connected through said tubular portion of said lower receptacle member to the upper portion of said upper receptacle member, and a helical shaped heat distributing plate positioned in said recess between said super-

heating coil and the side wall of the recess of said lower receptacle member.

In testimony whereof, I have hereunto ¹⁰ set my hand at San Diego, California, this 14 day of July, 1922.

ANDREW R. BLACKSTONE.
